UNITED STATES PATENT OFFICE.

SALVATORE FERRAGAMO, OF HOLLYWOOD, CALIFORNIA.

DESIGN FOR A TOP FOR AUTOMOBILES.

Application filed December 3, 1925. Serial No. 15,625. Term of patent 14 years.

To all whom it may concern:

Be it known that I, SALVATORE FERRAGAMO, a subject of the King of Italy, residing at Hollywood, in the county of Los Angeles and State of California, have invented a new, original, and ornamental Design for a Top for Automobiles, of which the following is a specification, reference being had to the accompanying drawing, forming part thereof, and wherein the figure is a perspective view of the top applied to an automo-

bile of the so-called coupé type, the body of the automobile being indicated by dotted lines.

I regard the rear side panel of the automobile top, and particularly the arrangement of the window panels and the bow as the essential feature of my invention.

I claim:

The ornamental design for a top for automobiles, as shown.

SALVATORE FERRAGAMO.
